Primary Examiner — Paula Greene(74) *Attorney, Agent, or Firm* — Plumsea Law Group, LLC(57) **CLAIM**

The ornamental design for an audio component, as shown and described.

DESCRIPTION

FIG. 1 is a top perspective view of an audio component showing my new design;

FIG. 2 is a bottom perspective view thereof;

FIG. 3 is a front elevation view thereof;

FIG. 4 is a top plan view thereof;

FIG. 5 is a side elevation view of one side thereof; and, FIG. 6 is a side elevation view of the opposite side thereof. The evenly spaced broken line portions show unclaimed subject matter only and form no part of the claimed design. The dot-dash broken line portions show the boundary between the claimed portion and unclaimed portions only and form no part of the claimed design.

1 Claim, 5 Drawing Sheets(56)
